COMBINED MINIATURE GREENHOUSE AND HUMIDIFYING RESERVOIR THEREFOR

Kanji Hitomi, 1216 56th Ave., Sacramento, Calif. 95831

Filed Aug. 27, 1975, Ser. No. 608,029

Term of patent 14 years

Int. Cl. D11—02

U.S. Cl. D35—3 A

FIG-1

FIG-2

FIG-3

FIG-6

FIG-5

FIG-4

FIG. 1 is a rear perspective of a combined miniature greenhouse and humidifying reservoir therefor, showing my new design;

FIG. 2 is a front elevation thereof;

FIG. 3 is a cross-section taken on line 3—3 of FIG. 2;

FIG. 4 is a side elevation, the opposite side being a mirror image thereof;

FIG. 5 is a rear elevation thereof; and

FIG. 6 is a top plan view thereof.

The potted plant is illustrated in broken lines in FIG. 1 for illustrative purposes only.

I claim:

The ornamental design for a combined miniature greenhouse and humidifying reservoir therefor, as shown and described.
